CLAIM

The ornamental design for a computer cabinet, substantially as shown and described.

DESCRIPTION

FIG. 1 is a view in perspective of a computer cabinet showing our new design;

FIG. 2 is a view in top plan thereof;

FIG. 3 is a side elevational view thereof as seen from the bottom looking up of FIG. 2;

FIG. 4 is a side elevational view thereof as seen from the side opposite that shown in FIG. 3; and

FIG. 5 is a side elevational view thereof as seen from right to left of FIG. 3, the side opposite that shown being a mirror image. The bottom not shown is substantially plain.

FIG. 1

FIG. 2

FIG. 3

FIG. 4

FIG. 5
